UNITED STATES PATENT OFFICE.

HERBERT W. HODGDON, OF PITTSBURGH, AND HENRY G. GILES, OF McCANDLESS TOWNSHIP, ALLEGHENY COUNTY, PENNSYLVANIA; SAID GILES ASSIGNOR TO SAID HODGDON.

PORTIONING MECHANISM.

1,334,304.

Specification of Letters Patent. Patented Mar. 23, 1920.

Application filed August 23, 1918. Serial No. 251,163.

To all whom it may concern:

Be it known that we, HERBERT W. HODGDON and HENRY G. GILES, citizens of the United States, and residing, respectively, in the city of Pittsburgh and in the township of McCandless, in the county of Allegheny and State of Pennsylvania, have invented or discovered new and useful Improvements in Portioning Mechanism, of which the following is a specification.

The invention consists in certain new and useful improvements in machines for dispensing portions of substances, such as portions of butter for individual customers.

The dispensing machine, which is the subject of this application, is intended for use in restaurants and hotels where large quantities of butter are used and it is desirable to serve the individual customers in an economical and sanitary manner.

More particularly the present invention comprises improvements in the means for severing the individual portions and in the means for discharging the severed portions from the machine.

Other novel features of construction and arrangement of parts will appear from the following description.

In the accompanying drawings, which are intended to illustrate the principles of the present invention Figure 1 is a vertical section of the improved machine taken along the line I—I in Fig. 2; Fig. 2 is a broken front elevation of the machine, and Fig. 3 is a perspective showing the bottom view of one of the blade carriages.

The following is a detailed description of the drawings:

A represents one or more boxes, open at its ends, and of any desired cross sectional shape. Thus if the butter or individual portions are to be square or round the cross sectional shape of the box corresponds thereto, so that a slab of butter of the proper cross sectional shape to form the desired pat will fit in the box. B is an outer container having a closed end and wholly or partially surrounding the boxes A. The boxes A and the container B may be conveniently cast integrally of metal.

1 is a lid for the container B which also closes the end of the boxes A and is provided with a hole 2 in alignment with the axis of each of said boxes. 3 is a cord extending down through each of said holes and having

attached to its inner end a weight 4 which rests upon the slab of butter in the box, thus insuring its proper intermittent descent in the box as its butt is severed into individual portions. The weight arrangement is of course used only where the boxes are vertical or set at an incline.

The ends of the boxes A open through the closed end of the container B, as shown in Fig. 1, and the container is provided with 65 slideways 5 running from front to rear, and one of said slideways intersecting the open end of each box. In each of said slideways is mounted a movable carriage or frame 6 provided with a forwardly extending stem 70 or handle 7 which protrudes from the front of the machine. 8 is a keeper plate for each carriage, having transverse slots 9 near each end engaged by screws 10 which engage threaded holes in the front of the machine. 75 At its center, the plate 9 is provided with a slot 11 extending inwardly from the bottom edge of the keeper plate. When the screws 10 are loosened the keeper plate may be raised and the carriage 6 may be withdrawn from the slideway, but when the plate is dropped with the slot 11 straddling the stem 7 and the screws 10 are tightened, the carriage cannot be withdrawn but its forward movement in relation to the machine is limited by the keeper plate. The carriage is normally held in its forward position against the keeper plate by means of a lever 12 which engages the inner end of the carriage and is pivoted on a stud 13 extending from the container bottom. A helical spring 14 is mounted on said stud and engages said lever, so that to force the carriage back along the slideway, the spring must be compressed.

15 is the spacing blade mounted in the carriage in such a position that when the carriage is in its forward position, the butt of the slab of butter in the corresponding box A is supported by or seats against said blade. 100 The spacing blade is spaced away from the open end of the box A a distance equal to the thickness of the portion of butter to be served. In the forward portion of the carriage a slicing blade 16 is mounted snugly 105 up against the end of the container. The rear or cutting edge of said blade has its inner face straight while its outer face is beveled at an acute angle as shown in Figs. 1 and 3, the bevel ending in a transverse an-

gular shoulder 17. The two blades 15 and 16 preferably overlap slightly as shown in Fig. 1. 18 is a stop block extending from the container B in the path of the blade 16 to limit the inward movement of the carriage, the front edge of the block being notched, as at 19 to prevent injury to the cutting edge.

20 represents shields or curved sheet metal members secured to the bottom of the container B and intersecting the paths of the carriage, said shields being cut away to provide clearance for the carriage.

21 represents an individual butter plate which has been placed in alignment with the box A, and 22 represents an individual pat or portion of butter which has been severed and deposited upon said plate 21 by the machine.

C represents a slab of butter of proper cross section to fit the box A, the weight 4 resting upon the top end of said slab.

The operation of the improved machine is as follows: In each of the boxes A is placed a slab C of butter whose butt protrudes from the lower end of the box and is supported by the spacing blade 15. The weights 4 are let down on top of the butter slabs in each box, the container is filled with cracked ice or other refrigerant, and 30 the lid 1 is put in position.

When a waitress desires to serve a customer with butter, she places a butter plate beneath one of the boxes A and pushes the corresponding stem 7 inwardly until the carriage is halted by the stop block 18. The result is that the slicing blade 16 is forced through the protruding butt of the butter slab close up against the bottom of the box A, thus severing the desired portion 40 which falls down on to the waiting butter plate. The beveled and shouldered cutting edge of the slicing blade prevents the severed pat from sticking to the under side of the slicing blade and the stop block 18 also 45 strikes against the rear edge of the pat should it fail to properly fall, thus knocking it loose. As soon as the waitress releases the stem 7, the spring throws the carriage forwardly, thus moving the slicing 50 blade 16 out from beneath the slab of butter and permitting said slab to descend in the box until its butt again rests upon and is supported by the spacing blade 15 which has again advanced into its first described 55 position. The shield 20 prevents the severed portion from being thrown forwardly from under the machine and directs it downwardly to the waiting plate.

In the embodiment of the machine shown 60 in the drawings, the boxes A are vertical, so that gravity is used to cause the intermittent movement of the slabs after each severing operation, but it will be under-

stood that the plane of the boxes is not important as any convenient means may be employed to advance the product through the boxes.

It is evident from the foregoing that uniform pats are delivered by machine in a most sanitary manner, no handling of the pats by the waitress being involved. Great economy both in butter and in the waitress's time is effected.

The machine may be readily taken apart and cleansed at frequent intervals. Its construction is simple, inexpensive and comprises no parts which will easily wear out or become broken even by careless use.

What I desire to claim is:—

1. In a dispensing machine of the character described the combination of a box having an open end and adapted to contain a block of butter, a carriage slideable transversely of the open end of said box and having mounted therein a supporting plate, adapted to support the block of butter when the carriage is in its normal position, a slicing blade mounted in said carriage and provided with a cutting edge which is adapted to cut through the butt of said block of butter when the carriage is moved out of its normal position, and a beveled block rigidly secured to the box with its forward edge spaced from the bottom of said box and in alignment with one wall of the opening therethrough, the cutting edge of said slicing blade adapted when moved to be received between the block and the bottom of the box thereby limiting the cutting movement thereof, said block also constituting a backing for the block of butter during the cutting operation.

2. In a dispensing machine of the character described the combination of a box having an open end and adapted to contain a block of butter, a carriage slideable transversely of the open end of said box and having mounted therein a supporting plate, adapted to support the block of butter when the carriage is in its normal position, a slicing blade mounted in said carriage and provided with a cutting edge which is adapted to cut through the butt of said block of butter when the carriage is moved out of its normal position, and a stop block rigidly secured to the bottom of the box adjacent the opening therethrough to limit the cutting movement of the blade depending in the path of said slicing blade and slotted to admit the cutting edge of the latter, said block also constituting a backing for the material to be cut.

Signed at Pittsburgh, Pa., this 22nd day of August, 1918.

HERBERT W. HODGDON.
HENRY G. GILES.
